(57) **CLAIM**

The ornamental design for an automated teller machine, as shown and described.

DESCRIPTION

FIG. 1 is a perspective view of an automated teller machine, showing our new design.

FIG. 2 is another perspective view of an automated teller machine of FIG. 1.

FIG. 3 is a front view of the automated teller machine of FIG. 1.

FIG. 4 is a rear view of the automated teller machine of FIG. 1.

FIG. 5 is a left side view of the automated teller machine of FIG. 1.

FIG. 6 is a right side view of the automated teller machine of FIG. 1.

FIG. 7 is a top view of the automated teller machine of FIG. 1; and,

FIG. 8 is a bottom view of the automated teller machine of FIG. 1.

The broken lines shown in the drawings represent portions of the automated teller machine that form no part of the claimed design.
